ATTORNEY

UNITED STATES PATENT OFFICE.

CHARLES E. STEWARD, OF WICHITA FALLS, TEXAS.

WHEEL.

Application filed March 16, 1923. Serial No. 625,527.

To all whom it may concern:

Be it known that I, CHARLES E. STEWARD, a citizen of the United States, residing at Wichita Falls, in the county of Wichita 5 and State of Texas, have invented new and useful Improvements in Wheels, of which the following is a specification.

This invention relates to improvements in power mechanisms and has particular 10 relation to rotary means which may be substituted for reciprocatory means used in the transmission of power.

More specifically stated, the invention aims to provide an eccentric wheel which 15 may be substituted for a crank arm, walking beam and the like and is especially adapted for use in well drilling, pumping and other machinery of an analogous character.

20 In addition, the invention aims to provide an eccentric wheel for the above purpose which is simple in construction, may be readily secured upon a shaft and in which friction is reduced to a minimum.

25 With the above and other objects in view, the invention further includes the following novel features and details of construction, to be hereinafter more fully described, illustrated in the accompanying drawings 30 and pointed out in the appended claim.

In the drawings.

Figure 1 is a side elevation of a wheel constructed in accordance with the invention, parts being broken away to more 35 clearly show the structure.

Figure 2 is an edge view of the wheel.

Figure 3 is a section.

Figure 4 is a view similar to Figure 1 showing a modified form of wheel.

40 Figure 5 is an edge view of the wheel shown in Figure 4.

Figure 6 is a sectional view of the same.

Figure 7 is an enlarged section on the line 7-7 of Figure 6 showing the form of 45 joint between the wheel sections.

Figure 8 is a detail section showing a modified form of bearing.

Referring in detail to the drawings, wherein like characters of reference denote 50 corresponding parts, the form of the invention shown in Figures 1 to 3 comprises a wheel which includes a hub 10 and a rim 11, the latter being mounted and rotatable upon the former. In this form of the invention the hub is of solid construction and 55 is provided with a bearing opening 12 which

is eccentrically located, oppositely extending flanges 13 serving to provide increased bearing surface to insure a true running wheel and to add to the strength and stability of the shaft 12 upon which the wheel is secured. The hub may be secured upon the shaft by means of a key or other suitable means. The outer edge of the hub is preferably provided with oppositely disposed marginal flanges 14 which form a relatively wide bearing surface.

The rim 11 in this form of the invention is of a sectional formation and includes an annular section 15 which is substantially 70 L-shaped in cross section and which provides a rim having an annular flange 16 extending from one edge thereof. The opposite edge of the rim is recessed as at 17 to provide a seat for a removable flange 18 75 which is spaced from the flange 16 so that an annular channel is provided which receives the outer edge of the hub 10.

Located within the channel just described are antifriction devices in the form of rollers 19, while the inner walls of this channel are provided with recesses for the reception of packing rings or washers 20. These rings or washers 20 bear against the outer edges of the flanges 14 and act as a means 80 for retaining lubricant within the channel so as to provide for free rotary movement of the rim upon the hub. The flange 18 is removably held in place by means of 85 bolts 21.

The outer edge of the rim 11 is provided with an annular groove 22 for the reception of a cable or other flexible element 23, which may in turn be engaged over a pulley or like member.

90 In the modified form of the invention shown in Figures 4 to 7 inclusive, the hub 10^a is of sectional formation, being split diametrically. The contacting edges of the sections are connected by a substantially 100 V-shaped joint 24, as shown in Figure 7 and are held together by means of bolts which pass through laterally extending flanges 25.

The rim 11^a is also of sectional formation 105 and the sections are joined by a V-shaped joint 26 and like the joint of the hub have flanges 27 extending therefrom for the passage of fastening bolts.

In the form of the invention just described, the wheel may be attached to a jack or other shaft without removing the shaft.

Like the first described form of the invention, suitable anti-friction rollers or similar devices 28 are interposed between the hub and the rim.

5 If desired, other anti-friction devices may be used with either form of the invention, one of such devices being shown in the form of a metal ring 29 in Figure 8 of the drawings. This ring may be annular in form or 10 may consist of two or more sections, as desired.

The invention is susceptible of various changes in its form, proportions and minor details of construction and the right is here- 15 in reserved to make such changes as properly fall within the scope of the appended claim.

Having described the invention what is claimed is:

A wheel comprising a hub, a sectional 20 rim rotatable thereon, said rim comprising an annular member substantially L-shaped in cross section and providing a rim portion and a flange at one edge thereof, a flange removably secured to the opposite edge of 25 said rim portion and spaced from the first mentioned flange to provide an annular hub-receiving channel and lubricant retaining rings interposed between the inner walls of the channel and the opposed faces of the hub.

In testimony whereof I affix my signature.
CHARLES E. STEWARD.
